CLAIM

The ornamental design for a planter, substantially as shown.

DESCRIPTION

FIG. 1 is a perspective view, from the top and two sides, of a planter showing our new design;

FIG. 2 is a perspective view thereof, from the bottom and the other two sides; and

FIG. 3 is a perspective view thereof, from the top and two sides, showing the planting trays in extended condition.

FIG. 1

FIG. 2

FIG. 3
